COMBINED HANDBAG AND COVER THEREFOR

Mitchell R. Bienen, New York, N. Y.

Application June 21, 1951, Serial No. 15,626

Term of patent 7 years

(Cl. D87—3)

To all whom it may concern:

Be it known that I, Mitchell R. Bienen, a citizen of the United States of America, residing in New York, county of New York, and State of New York, have invented a new, original, and ornamental Design for a Combined Handbag and Cover Therefor, of which the following is a specification, reference being had to the accompanying drawing, forming part thereof.

Fig. 1 is a front perspective view of a combined handbag and cover therefor embodying my new design;

Fig. 2 is a perspective view of the cover portion;

Fig. 3 is a front perspective view of the handbag with the cover removed and with the handle broken away for convenience of illustration; and

Fig. 4 is a bottom plan view, on a reduced scale, of the cover portion.

The back of the combined handbag and cover therefor is substantially the same in appearance as the front aside from the clasp element.

I claim:

The ornamental design for a combined handbag and cover therefor, substantially as shown and described.

MITCHELL R. BIENEN.
